UNITED STATES PATENT OFFICE.

JOHN J. WEITHAUS, OF NORTH VERNON, INDIANA.

LIQUID-HYDROCARBON-VAPOR PRODUCER.

1,337,108.

Specification of Letters Patent. Patented Apr. 13, 1920.

Application filed February 9, 1917. Serial No. 147,639.

To all whom it may concern:

Be it known that I, JOHN J. WEITHAUS, a citizen of the United States, residing at North Vernon, Jennings county, and State 5 of Indiana, have invented and discovered certain new and useful Improvements in Liquid - Hydrocarbon - Vapor Producers, of which the following is a specification.

My invention relates to liquid hydrocarbon vapor producers and its object is to provide means for cheaply and effectively producing a vapor from liquid hydrocarbon.

With this object in view, my invention is embodied in preferable form in the construction hereinafter described and illustrated in the accompanying drawings.

In the drawings, the view shown is a side view in elevation, partly in vertical section, illustrating a plant embodying my invention.

Referring to the drawings, 1 indicates a tank adapted to contain compressed air, which air is supplied from a suitable inlet pipe 2 leading from any suitable means of 25 air compression. An outlet pipe 3 leads from the upper end of this tank and is provided with a gage 4 and with a main feeding pipe 5 in which is mounted a cut-off valve 6. The main section of the pipe 5 joins a depending branch 7 which leads by 30 means of suitable angle sections into and through a gas forming and liquid hydrocarbon containing tank 8. The pipe 7 leads through the bottom of this tank and through 35 the body 9 of gasoline, kerosene, fuel oil, or other liquid hydrocarbon to be vaporized. The lower end of pipe 7 is open and leads into a larger pipe 10 which communicates at its upper end with the tank 8. Leading 40 from the pipe 10 preferably at a point immediately opposite the termination of the pipe 7 is a liquid hydrocarbon and air conveying pipe 11 having a valve 12. The compressed air emerging from the lower end of 45 pipe 7 aids and forces gasoline through the pipe 11. The pressure in the tank 8 is from twenty-five to one hundred and fifty pounds and hence the air will not escape upward in the tank through the liquid.

The pipe 11 connects with a series of coils 50 mounted in a vaporizer or heater 14 which is adapted to vaporize the liquid hydrocarbon passing through the coils so as to produce a vapor. This heater is heated 55 by a burner 15 supplied with vapor by a pipe 16 adapted to communicate with the

main vapor supply pipe 17. A vapor conveying pipe 18 leads from the coils. This pipe leads through a chamber 19 through which the pipe 7 also passes and which 60 chamber communicates directly with the tank 8. The pipe 18 is of sufficient length to cool the vapor from the vaporizer before it enters the tank 8, thereby obviating the danger of explosion which might exist if a 65 highly heated vapor were introduced into the tank.

The vapor or gaseous mixture thus introduced into the tank 8 serves to enrich and densify the liquid hydrocarbon vapor within 70 the tank. The vapor produced rises into small gas domes or chambers 19' and 20 projecting from the upper end of the tank 8. These gas domes communicate by pipes 21 and 22, respectively, controlled by valves 75 23 and 24, with the main vapor feed line pipe 17 which leads to a reservoir and an engine or other suitable means to which gas is to be supplied for power, heat, or lighting purposes.

In order to maintain the pressure in the tank, a pipe 25 leads from the main air pressure pipe 5 down into the lower part of the tank 8 through the dome 20 and a similar pipe 26 leads from the main air 85 pressure pipe 5 down through the dome 19. These pipes 25 and 26 supply vaporizing air for the production of the hydrocarbon vapor within the tank and maintain the necessary pressure for the flow of the liquid hydrocarbon. Leading from the pipe 26 is an 90 exhaust or safety pipe 27 adapted to permit an excess gas pressure in the tank to be relieved. In such operation the valve 28 is first closed. The pipes 26 and 25 are provided with cutoff valves 28 and 29 respectively, adapted to shut off the flow of air from the main pressure pipe to the tank when desired. In operation either or both of the valves 28 and 29 may be throttled or 100 fully open, the air pressure transmitted through the pipe 7 being at all times sufficient to force air and oil into pipe 11. Leading into the upper part of the tank 8 below the upper level of the latter is a liquid 105 hydrocarbon inlet pipe 30 controlled by a valve 31 and which also may be used to permit the escape of the gas when the pressure becomes excessive.

In the operation of the device, the tank 3 110 being supplied with a suitable amount of gasoline, kerosene, or other liquid hydro-

carbon fuel 9, the compressed air is admitted from the tank 1 into the main air pressure pipe 5 and thence passes down through the pipes 25 and 26 to supply air to vaporize the liquid hydrocarbon and maintain the necessary pressure in the tank for feeding. The air under pressure is led through the pipe 7 and into the pipe 10 at the bottom of the tank 8 forcing air and liquid hydrocarbon through the pipe 11 and into the coils 13 mounted in the heater 14 where the mixture is vaporized and heated and then conducted back through the pipe 18, where the mixture is cooled and then led into the tank 8 above the liquid hydrocarbon for the purpose of regenerating and enriching the vapor being formed therein and assisting in the formation of the vapor. Any unvaporized particles of liquid hydrocarbon that may pass from the pipe 18 and chamber 19 into the tank 8 will, owing to their greater weight, descend to the bottom of the chamber while the gaseous matter will rise mingling with the vapor above the body of liquid. The pressure of the air within the tank 8 will cause the vapor to rise and collect in the domes 19 and 20, thus from these domes the completed vapor is led by the pipe 17 to a suitable means of utilization.

Having thus described my invention, what I claim is:

1. In combination with a vessel containing air under continuous pressure, a liquid hydrocarbon containing tank, a main air pipe leading from said source into said tank, a liquid hydrocarbon conduit pipe opening

from the lower end of said tank, the open end of said air pipe projecting down into said liquid hydrocarbon conduit, air conveying pipes leading into the tank from the main air line and terminating above the liquid, cutoff valves in said pipes, an external vaporizer including a coil through which hydrocarbon is led and a heater for said coil, a cooling and conveying pipe leading from the vaporizer back to the tank above the level of the liquid and means for drawing off the vapor from the upper end of the tank.

2. In combination with a vessel containing air under continuous pressure, a liquid hydrocarbon containing tank, a main air pipe leading from said vessel into said tank, a liquid hydrocarbon conduit pipe opening from the lower end of said tank, air conveying pipes leading into the tank from the main air line and terminating above the liquid, cutoff valves in said pipes, an external vaporizer including a coil through which hydrocarbon is led from said tank and a heater for said coil, a cooling and conveying pipe leading from the vaporizer back to the tank above the level of the liquid and means for drawing off the vapor from the upper end of the tank.

In witness whereof I have hereunto set my hand and seal at Indianapolis, Indiana, this 5th day of February, A. D. nineteen hundred and seventeen.

JOHN J. WEITHAUS. [L. S.]
